UNITED STATES PATENT OFFICE.

KASIMIR VOGEL, OF CHELSEA, MASSACHUSETTS, ASSIGNOR TO THE VOGEL ELECTRIC INSULATING AND MANUFACTURING COMPANY, OF PORTLAND, MAINE.

MACHINE FOR COVERING WIRE, CORD, &c.

SPECIFICATION forming part of Letters Patent No. 437,266, dated September 30, 1890.

Application filed April 14, 1890. Serial No. 347,756. (No model.)

To all whom it may concern:

Be it known that I, KASIMIR VOGEL, of Chelsea, in the county of Suffolk and State of Massachusetts, have invented a new and useful Improvement in Machines for Covering Wire, Cord, &c., which will, in connection with the accompanying drawings, be hereinafter fully described, and specifically defined in the appended claims.

10 In said drawings, Figure 1 is a perspective view of my newly-invented machine; and Fig. 2 is a longitudinal section thereof, taken through the axis of the hollow spindle.

The object of my invention is to provide an effective machine for the purpose specified without employing the usual expensive and complicated machines heretofore employed for such purpose, in which are arranged a plurality of bobbins which not only travel 15 around the wire or cord that is being covered, but also change relations to each other for the purpose of effecting an interlacing of the thread of the several bobbins, each with the others, as they unitedly overlie the wire that 20 is being thereby covered. These results I accomplish by the devices and the combinations thereof that will, in connection with the drawings, be hereinafter described and claimed.

Referring again to said drawings, A represents the frame, which may be secured to a bench or stand. In said frame is journaled the hollow spindle *a*, formed with the internal tube *d*, and with the shorter external tube *b*, rigidly secured on the longer tube *a* and journaled in the bearing *c c* of frame A. Upon the exterior tube *b* is secured the pulley B, by which the spindle is rotated through the agency of a belt or cord. Within tube *a*, I arrange tube *d*, the external diameter whereof 30 is slightly less than the internal diameter of *a*, so as not to cause friction between the two when *a* is revolved. At the lower end of tube *d* it is enlarged, as at *e*, either by securing a collar upon it or by forming it with such enlargement, and I form in *e* the seats *f*, having flat parallel bases, against which the inner faces of the forks of holder *g* bear. Said holder 35 is secured to frame A, and serves to hold the inner tube *d* non-rotative.

The wire or cord that is to be covered is shown at *h* as passing up through tube *d* and out at the top of tube *a* and as being wound upon a bobbin by the winding device E. The thread-bobbin is shown at D, and the thread *m* as wound thereon. Said bobbin is arranged 50 axially on spindle *a* and rests upon the base-plate *i* of the flier-frame C, which plate is by its hub *j* secured rigidly on the lower portion *b* of the spindle *a*, so as to support both the flier-frame and bobbin. Said flier-frame is 55 formed with said base-plate *i* and a top ring *l*, the two being united by the rods *k*, secured therein, as shown, the central opening in ring *l* being of a size to freely admit bobbin D, which, as stated, fits loosely upon spindle 60 *a* and rests upon plate *i*, the friction between the bobbin and plate causing the two to travel together, except when the taking up of the thread *m* upon wire *h*, as will be explained, causes the bobbin to revolve slowly on the 65 plate.

The machine being put in order for use and wire *h* being carried from below up through arbors *d* and *a* and connected with winder E, the end of thread *m* is brought out between 70 two of the rods *k*, and, being carried spirally around the winder to the requisite extent, is then passed through passage *n* in ring *l*, whence it passes through opening *p* in arbor *a* and is secured to the wire, when by rotating the 75 flier-frame in a direction opposite to the upward spiral path of the thread outside of rods *k* the thread will be wound upon the wire to a thickness due to the size of the thread and the relative velocity of the rotation of the 80 flier-frame and the lineal movement of the wire.

It will be obvious that if the flier-frame be rotated in the direction indicated by the arrow on plate *i* the thread will not only be 85 held under tension upon rods *k*, but that the bobbin will be slowly rotated upon plate *i* in a direction opposite to the direction of rotation of the flier-frame as the thread is wound upon the wire. If it be desired to saturate the covering-thread with an adhesive or water-proof substance, a fountain F may be arranged below the arbor and filled with 90 95

such adhesive substance, so that the wire *h* will pass up through the same, taking along the requisite portion to saturate the thread.

By arranging the axis of the spindle oblique instead of vertical the friction of the bobbin upon plate *i* is less variable, as the thread thereon varies in quantity and weight, for if the spindle were vertical the friction would be in the direct ratio of the weight of the bobbin, while if it were horizontal the friction upon plate *i* would be zero, and hence by arranging the spindle obliquely the friction is, as stated, more nearly uniform.

My machine is not only adapted to cover wire of various sizes with insulating material, but it is equally adapted to the purpose of covering cord with an ornamental covering of any desired kind and for all analogous uses and purposes.

Having thus described my invention, what I claim as new, and desire to secure by Letters Patent, is—

1. The combination of frame *A*, hollow spindle *a*, having a thread-passage through its wall near its top, pulley *B*, flier-frame *C*, formed with base *i*, top ring *l*, having a thread-pas-

sage *n* therein, and rods *k*, uniting said plate and ring, tubular guide *d*, arranged in said spindle and held non-rotative, and a reservoir *F*, arranged below guide *d*, and spindle *a* to co-operate therewith, substantially as specified.

2. In a machine of the class specified, the combination, with the hollow arbor formed with a transverse thread-passage near its top, of the flier-frame mounted on said arbor and formed with a base to support the bobbins and with a ring secured to said base by supporting-rods and formed with a central opening to receive the bobbin, and with a thread-passage, substantially as specified.

3. In a machine of the class specified, and in combination with the flier-frame formed with a base to support and duly friction the bobbin for requisite thread tension, the hollow spindle which serves as the axis of the flier-frame, arranged with its axis oblique to a vertical line, substantially as specified.

KASIMIR VOGEL.
